By L. M. Shurlock,

UNITED STATES PATENT OFFICE.

OLIVER H. CLOYD, OF PEORIA, ILLINOIS.

HOG-GREASER.

1,142,798.

Specification of Letters Patent. Patented June 15, 1915.

Application filed July 15, 1912. Serial No. 709,522.

To all whom it may concern:

Be it known that I, OLIVER H. CLOYD, citizen of the United States, residing at Peoria, in the county of Peoria and State 5 of Illinois, have invented certain new and useful Improvements in Hog-Greasers; and I do hereby declare that the following is a full, clear, and exact description of the invention, which will enable others skilled in 10 the art to which it appertains to make and use the same.

This invention has reference to that class 15 of devices known as rubbing posts or hog greasers, and relates to an apparatus for applying a grease or disinfectant to hogs or other stock.

An object of the invention is to provide 20 a device that will be self feeding in that the oil or disinfectant will be fed automatically to the outer surface of a member upon which the animal rubs by a novel arrangement of parts.

Another object is to produce a device of 25 the class described of exceedingly simple construction requiring little or no machine work in consequence of which it can be built at low cost.

Another object is to provide in a hog 30 greaser a part which, when pressure is applied thereto, will cause the liberation of a supply of oil or disinfectant which will flow upon the outer surface of said part, the flow being automatically interrupted when the pressure is removed.

Still another object is to improve upon 35 devices of this class by providing a structure as distinguished from the known art, in which the fluid held within the device is made to discharge upon the outer side or 40 outer surface of a member or part upon which the animal will naturally rub whereby the fluid will be directly applied to the affected parts after being discharged from the receptacle.

Besides the above objects the invention 45 relates to certain details of construction and arrangement of parts as will be clearly brought out.

In the accompanying drawing forming 50 a part of this application, Figure 1 shows the complete device in perspective. Fig. 2 is a sectional elevation of a part of the same. Fig. 3 is a face view of one of the rubbing parts. Fig. 4 is a sectional eleva-

tion of certain portions of the device. Fig. 55 5 is a plan of a rotating part and associated parts. Fig. 6 is a side elevation of the same, and Fig. 7 is an end elevation of a part of the mechanism shown in Figs. 5 and 6.

A indicates an upright hollow body or post, 60 preferably a casting, comprising the main body provided with a closure at its top such as a cap B, for example, which may be removed for the introduction of the fluid such as an oil or disinfectant. At its lower end 65 the post or body is preferably reduced in size and terminates in a tubular extension C whose interior communicates with that of the said post or body and suitable ribs D, E, Fig. 4 serve to strengthen the extension 70 and provide for a proper rigid connection with the body. The extension C is preferably smaller in diameter than the post or body in order that the amount of the solution necessary to fill the entire device 75 can be kept as small as possible, and it being only necessary that the extension C be of sufficient diameter to feed the solution to the parts at the outer end of the extension about to be described. These parts consist 80 first of an upwardly extending neck G terminating in a hollow horn or nose H. The latter for purposes of ease of manufacture is preferably a separate part that can be secured to the upturned portion or neck 85 G by means of bolts J extending through ears K on both the parts as clearly illustrated in Fig. 6.

L indicates an aperture in the lower wall of the horn or nose into which the tapered 90 end of a screw M is adapted to seat and by which the amount of oil or disinfectant discharged through the said aperture can be regulated.

N indicates two arms extending from and 95 preferably cast with the portion C between whose outer extremities a receptacle O is pivoted by means of a pin or shaft P, extending through depending ears Q, carried by said receptacle. The wall of the latter 100 adjacent the horn or nose H is provided with a projecting gutter R adapted to fit the said lower wall of the said horn or nose H to cover and close the opening L. For the latter purpose I preferably use a pad of 105 felt or other soft material indicated at S in Fig. 7. In the wall of the said receptacle is an opening 2 through which said gutter

directs the oil or disinfectant into the receptacle. Extending from the said receptacle and overhanging the gutter and the horn or nose is an apron T provided with an opening U through which the screw M may be reached and adjusted.

Rotatably mounted in the receptacle by means of a pin or shaft V is a fluted or roughened roller W. Extending between 10 and preferably cast with the arms M is a bridging piece 3 which lies beneath the receptacle O. This is provided with an upwardly extending lug 4 carrying an expanding spring 5 constantly tending to 15 hold the gutter R against the nose or horn to close the said opening L.

Cast with and extending outward from the upper portion of the post or body A is a series of hollow extensions 6 which communicate with the interior of the latter as shown in Fig. 2 for receiving the oil or disinfectant therefrom. Each of the portions includes a depending part 7 provided with a hole 8 extending through both of its walls. 20 A screw 9 engages in the hole of the outer wall and its inner end is designed to enter the hole of the inner wall to regulate the flow of the oil or disinfectant through the same and it is observed that a recess is provided between the depending part 7 and the body A. A rubbing member consisting of a plate 10, for example, is pivoted at its lower end in any suitable manner to a lug 11 cast with the body A and its upper extremity lies 25 in the said recess substantially as shown. The surface of the said member 10 lying opposite the opening 8 is preferably provided with a piece of felt or other soft material 12 constituting a valve which will serve to close 30 the said opening and prevent leakage there being a spring 13 interposed between the member and the wall of the body which constantly tends to hold the said member against the extension 7 to close said opening. Beneath the extension on the outer surface of 35 the member is a horizontally disposed rib 14 upon which the oil or disinfectant is deposited as it leaves the opening 8 whenever the latter is exposed, said rib serving to distribute 40 the oil or disinfectant upon the outer face of the said member 10. The face of the latter, as illustrated in Fig. 3, is provided with a plurality of vertically extending grooves 15 and communicating with them 45 are downward curved transverse grooves 15' which receive the oil as it runs over the rib 14 and distributes it over practically the entire face of the member. Cast with the body 50 A are pairs of lugs 16 near the hollow portions 6 one at each side of each member 10. These lugs prevent side motion of the members 10 caused by the stock rubbing against them. Thus constructed the entire device 55 may be mounted upon any suitable base 17 by means of bolts 18, for example, extend-

ing through the horizontal flanges E described.

The solution is introduced in the body A by the removal of the cap B and is maintained at a high level so that the members 6 70 will be properly supplied and, of course, the said body A may stand as high as desired and it may be of considerable capacity so that the solution will last a considerable length of time. The member 10 through the 75 spring 13 prevents the solution from escaping but the animal in placing his weight against it exposes the hole 8 to discharge some of the solution upon the rib 14. In running down upon and along the rib the 80 solution will be evenly distributed and thus in running down into the grooves 15 15' it will be distributed evenly over the entire surface against which the animal rubs. Upon removing the pressure the spring 13 85 will return the member 10 to its normal position or that for closing the opening 8. The oil or disinfectant, of course, will lie within the lower horizontal hollow portion D and in the horn or nose H so that the adjustment 90 of the screw M at the hole L will permit as much of the solution to flow through said opening as desired. The animal in rubbing his belly upon the roller W will force that member downward, together with the receptacle O, overcoming the pressure of the spring 5 and permitting the solution to flow into the gutter R from the opening 2 and from thence into said receptacle but when pressure is removed from the roller the opening 100 will be closed automatically due to the spring. The roller lies partially in the solution and in its rotation it will be kept coated therewith and cover the parts of the animal rubbed upon it.

The apron T overhanging the nose H and the gutter R prevents mud and dirt scraped from the animal's body reaching the gutter R. The hole U in said apron admits of the introduction of a screw-driver or other tool 110 for adjusting the screw M. However, other methods may be provided for adjusting the screw.

My device is distinguished from those of the art such as have a pivoted rubbing member on the wall of the post in control of a valve, by the fact that the place of discharge for the fluid is so located that the fluid is deposited upon the exterior surface of the member instead of on the rear or inner surface. When the place of discharge is at the outer surface of the member the fluid when discharged upon said outer surface is directly picked up by the animal and, as the irritation of the skin is relieved immediately the fluid covers the affected parts, the animal naturally removes the pressure upon the member and the discharge at once stops. The discharge opening is only held open long enough to permit enough fluid to be dis- 120 125 130

charged to serve the purpose. For this reason my device is very economical in the use of fluid since there is not chance for waste.

5. I may resort to various changes with regard to structural details in my improved rubbing post such as will lie within the meaning and intent of the invention and within the scope of the claims and

16. Having described said invention, I claim:—

1. In a rubbing post the combination of a receptacle for fluid including a depending tubular extension provided with a discharge opening facing toward the receptacle from which the fluid flows, a rubbing member for receiving a fluid from the opening and arranged to overlie and normally close said opening and adapted to be moved by pressure of an animal applied thereto for exposing said opening to permit the discharge of a fluid from said opening upon the surface that closes said opening.

2. In a rubbing post, the combination of a support including a holding portion for fluid and a communicating hollow extension having an opening facing toward the support, an elastically held rubbing member lying between the extension and the support, its outer surface upon which the animal rubs normally lying upon and closing the opening and adapted to expose the same by pressure of an animal thereon to permit the flow of fluid upon its said outer surface, or that upon which the animal rubs, said member being limited in its movement by the said extension and said support.

3. A rubbing post comprising a receptacle for a fluid, a conduit projecting from said receptacle and formed with an elbow having a discharge opening spaced from said receptacle, a rubbing member including a closure to control the opening, said rubbing member being arranged with respect to said opening whereby the fluid is deposited upon the surface thereof against which the animal rubs.

4. A rubbing post consisting of an elevated receptacle including a communicating tubular extension provided with a discharge opening spaced from the receptacle, and an elastically held member covering the opening and lying between said opening and said receptacle and adapted by pressure of an animal against it to expose the opening.

5. In a hog greaser, the combination of an elevated receptacle having an extended portion including a discharge opening facing the main portion thereof, a single rigid upright bar supported pivotally at one end and carrying a valve to overlie and normally close the opening, means to elastically hold the bar outward upon the said opening for closing the same, said bar adapted to be moved away from the opening by pressure

of an animal thereon to expose said opening, the latter being arranged with respect to the bar whereby fluid from it is deposited upon the outer surface of the bar or that surface upon which the animal places pressure.

6. In a rubbing post, in combination, a receptacle fixed in an upright position and provided with an opening in its side, means to adjust the size of the opening, a member elastically held upon the said opening to close it and adapted to expose the opening by pressure of an animal upon its side that overlies the said opening.

7. A rubbing post comprising in its construction a hollow arm for receiving and holding a fluid and including a depending portion having an opening in one of its vertical walls for the discharge of the fluid, an upright member having its front face overlying the opening, means to elastically hold the bar upon the opening, said bar adapted by pressure of an animal upon its front face to expose said opening for the discharge of the fluid upon said front face.

8. A rubbing post consisting of a body for containing oil or a disinfectant having a tubular extension in communication with it and provided with a discharge opening, a member lying opposite the opening and stationed between it and said body, and means to positively but yieldingly hold it upon the opening.

9. A rubbing post comprising a support, a rubbing member mounted thereon adapted to be moved relatively thereto by pressure of an animal against it, said support including a space for an oil or disinfectant and a communicating tubular part extending from and communicating with said space and having an opening in its wall facing the support and lying opposite the rubbing member and adapted to discharge its contents upon the surface upon which the animal rubs, said member adapted to normally close said opening.

10. In a rubbing post, in combination, a receptacle for oil or a disinfectant having a discharge opening, a rubbing member lying opposite said opening and adapted to normally cover and close the same and adapted to be moved to expose the opening by pressure of an animal against its side that covers said opening, said rubbing member including at that side a lip or flange extending across its face beneath the opening to receive the oil or disinfectant directly therefrom, said member being limited in its movement relatively to the receptacle.

11. In a rubbing post, a member for containing oil or a disinfectant having a discharge opening, an elastically held part opposite said opening and adapted to positively close the same adapted to be moved by pressure of an animal upon its side adjacent the opening and including a lip on that side

extending beneath the member, the oil flowing over said lip upon said part, and means to limit the movement of the part.

12. A rubbing post for live stock consisting of a hollow body having a hollow extension communicating with it near its upper portion, said extension including a discharge opening for the fluid, a member pivoted relatively to said receptacle and lying between said receptacle and said extension and opposite the opening, and means to normally hold the member upon said opening.

13. A rubbing post for live stock consisting of a receptacle for a fluid including a hollow extension at its side in communication with its interior, said extension including a depending portion and a discharge opening therein for the fluid, a member lying opposite the opening and between the said portion and the receptacle and adapted to normally close the opening, and means to yieldingly hold the member upon the opening.

14. A rubbing post for live stock comprising a receptacle for a fluid including a hollow extension communicating therewith, the latter including a discharge opening for the fluid, a member pivoted on the lower portion of the receptacle, its upper end normally lying upon the opening, the surface of said member having a series of grooves in its surface for distributing the fluid, and means to normally and yieldingly hold the member upon the said opening.

15. The combination in a rubbing post, of a receptacle for fluid, a member presenting a rubbing surface on one of its faces for the animal, and adapted for receiving fluid from said receptacle upon said surface and provided with a series of grooves extending in one direction, and a series of grooves extending in a different direction and communicating with the first.

16. The combination in a rubbing post, of a receptacle for a fluid including a depending hollow extension provided with an outlet opening in its side, a member pivoted relatively to the extension and normally covering the opening, and including a substantially horizontally disposed lip lying below the opening and said depending extension, and a spring to hold the member upon the opening.

17. In a rubbing post, a rubbing member consisting of a substantially vertically disposed bar adapted to receive a fluid at its upper end having a single groove in its surface extending vertically, there being a series of depressions communicating therewith and extending at an angle downward therefrom and adapted to receive the fluid from said single groove.

18. In a rubbing post, a rubbing member consisting of a substantially vertically disposed bar adapted to receive a fluid at its upper end having a single groove in its sur-

face extending vertically, there being a series of depressions communicating therewith and extending at an angle downward therefrom and adapted to receive the fluid from said single groove, there being a second vertical groove with which said series of depressions communicate and in which they terminate.

19. The combination in a rubbing post for live stock, of a vertically disposed receptacle, having at its upper portion a hollow extension provided with a discharge opening, a member pivoted at its lower end near the lower end of the receptacle for receiving pressure of an animal and arising to and at its upper end normally covering the opening and adapted to receive a fluid from said opening upon the surface against which the animal rubs, said surface being roughened, means to yieldingly hold the member upon the said opening, and means carried by the receptacle to guide the member.

20. In a rubbing post, the combination of a receptacle for containing a liquid having a part extending outward therefrom including a depending portion spaced from said receptacle, there being a discharge opening facing toward said receptacle, and a member lying between the depending portion and the receptacle opposite the discharge opening and having a rubbing surface, and adapted by pressure of an animal thereon to liberate the fluid from the opening, a portion of that side of said member having the rubbing surface receiving the liquid from said opening.

21. In a rubbing post, in combination, a receptacle for a fluid including a depending portion provided with an opening in its side, a rigid member movable relatively to the receptacle, and normally lying upon the opening, and means to positively limit its movement with respect to said depending portion, said member lying between the said means and the latter.

22. In a rubbing post, in combination, a receptacle for a fluid having an opening in its side, an elastically held member, one of its faces closing the opening and including a lip below said opening, a part opposite the member, said member lying between said part and the said receptacle and limited in movement by each.

23. In a hog oiler, the combination of a support and an elevated receptacle mounted thereon including an extended open nozzle in a position whereby fluid will be discharged therefrom by gravity, a member hingedly mounted on the support below the nozzle and normally and elastically held upon and closing the latter, said member having a recess in its upper portion to receive the same into it, an extended wall of the recess beneath the nozzle adapted by its position to receive the fluid from said nozzle upon it.

24. In a portable hog oiler, the combination with a receptacle including a nozzle having a discharge opening in position for the discharge of fluid by gravity, of a member pivotally mounted upon the structure below the nozzle and having a recess in its upper end, one of the walls of the recess adapted to overlie the opening of the nozzle, the lower wall of the member lying beneath the said nozzle and adapted to receive fluid

from the same, and means to hold the member normally upon the opening of the nozzle to close it.

In testimony whereof I affix my signature, in presence of two witnesses.

OLIVER H. CLOYD.
